UNITED STATES PATENT OFFICE.

YUSUKE TAMAMURA, OF TOKYO-FU, JAPAN.

CLIP FOR ROPEWAY CARS.

Application filed December 27, 1922. Serial No. 609,361.

To all whom it may concern:

Be it known that I, YUSUKE TAMAMURA, a subject of the Emperor of Japan, residing at No. 18 Genbei, Totsuka-machi, Toyotama-
5 gun, Tokyo-fu, Japan, have invented cer-
tain new and useful Improvements in Clips
for Ropeway Cars, of which the following
is a specification.

This invention relates to improvements
10 in gravity-operated clips for cars used on
ropeways, haulage tramways and the like.
Its object is to provide a clip which has
combined in it the essential properties of
the clips of different types and which in
15 engaging the rope will act firstly as an in-
tegral, then as a neutral, and lastly as a
differential clip, and will act in the reverse
order when releasing the rope.

The clip according to this invention re-
20 sembles in shape the differential clip in-
vented by me and for which patent was
granted in Japan as Patent No. 9,896 on
December 26th, 1905, in the United States
25 of America on April 16th, 1907, as Patent
No. 850,504, and in Great Britain as Patent
No. 1,565 of 1907. The construction of the
clip of this invention is, however, more com-
plicated than the one just referred to.

The clip according to this invention is
30 composed of a horizontal lever arm ending
in a clip-jaw, a vertical lever-arm ending
in another clip-jaw, and an intermediary
arm, the three arms and a connecting bar
35 forming four sides of a trapezoid quadri-
lateral of which the side formed by the in-
termediary arm is held fixed while the three
other sides are movable. The head-pin con-
necting pivotally the two clip-jaws and the
40 tail-pins of the vertical lever-arm, of the
intermediary arm and of the horizontal
lever-arm, form the vertices of the said
quadrilateral.

In a clip formed in this manner, when the
45 eye-bar forming the upper side of the tra-
pezoid turns upward in relation to the line
connecting the said head-pin and the tail-
pin of the horizontal lever-arm, which forms
the bottom of the trapezoid, the clip-jaws
50 will close and compress the hauling rope.
When the eye-bar turns downward in rela-
tion to the bottom, the clip-jaws will open
and release the hauling rope.

The accompanying drawings illustrate
55 the preferred embodiment of the present
invention. In said drawings—

Fig. 1 is a vertical section through a con-
struction embodying the invention;

Figs. 2 and 3 are a side view and plan
view, respectively, thereof;

Figs. 4 and 5 are views similar to Figs. 60
1 and 2, showing the arrangement in in-
operative position;

Figs. 6 and 7 are an end view and a side
view, respectively, of an arrangement used
65 in connection with a double rope system
for making the device of the invention in-
operative.

Fig. 8 is an end view of an arrangement
including the invention used in connection 70
with a single rope system.

Figs. 9 and 10 are a side view and plan
view respectively thereof.

Referring now more particularly to the
drawings, Figures 1 to 5 show my improved 75
clip adapted for use in the double rope sys-
tem. The clip comprises the vertical lever-
arm 7 provided with the jaw 5 and the
horizontal lever-arm 8 provided with the
jaw 6, the two jaws being pivotally con- 80
nected by means of the head-pin 11. The
tail-pin 10 of the horizontal lever-arm is
pivotally mounted on a bearer 13 provided
at the rear end of the main shaft 12 which
passes through the eye formed at the upper 85
end of the suspension bar 14. From the
said eye extends rearwardly a sleeve upon
which the intermediary arm 15 is operably
mounted. The arm 15 so mounted counter-
acts the moment due to the weight of the 90
receptacle. The tail rod 16 is screwed to
the intermediary arm 15 which extends ob-
liquely to the main shaft 12, and a pair of
eye-bars 18 is connected to the tail rod 16 by
means of the tail-pin 17. These eye-bars 95
18 which connect the tail-pin 17 of the inter-
mediary arm 15 with the tail-pin 9 of the
vertical lever-arm 7, serve to transmit com-
pression from the intermediary to the ver-
tical lever-arm. The line of the said com- 100
pression intersects with the line of the re-
action of the hauling rope 1 as indicated by
the arrow heads in Figure 1. These two
forces are counter-balanced by the force act-
ing at the tail-pin 10 of the horizontal lever- 105
arm 8. The horizontal component of the
force acting at the tail-pin 10 is equal in
magnitude but opposite in direction to the
horizontal component of the force acting
at the tail-pin of the vertical lever-arm 7. 110

The excess of the vertical component of the force at the tail-pin 10 over the vertical component of the force at the tail-pin 9 is equal to the reactional force acting upwardly at the head-pin 11.

The moments around the head-pin 11 of the two forces acting at the tail-pins 9 and 10 are equal but opposite, being each equal to the product of the horizontal component of either of the two forces multiplied by the distance between the head-pin 11 and the point of intersection of the said three forces. These two moments cause the jaw-levers 7 and 8 to grip the hauling rope 1.

15 The set of four pins, that is to say, the tail-pin 10 of the horizontal lever-arm, the tail-pin 17 of the intermediary arm, the tail-pin 9 of the vertical lever-arm and the head pin 11 form the vertices of the trapezoid quadrilateral. The line of the eye-bars 18 which form the upper side of the trapezoid, indicates the line of action of the force at the tail-pin 9 of the vertical lever-arm. The clip will act differentially, inverse-differentially, or integrally, according as the extension of the center line of the eye-bars 18 cuts the bottom of the trapezoid formed by the line connecting the tail-pin 10 with the head-pin 11 at a point back of the pin 10, or 30 between the pins 10 and 11, or in front of the pin 11. When the center line of the eye-bars 18 is parallel to the bottom of the trapezoid, the action of the clip is neutral.

35 When the clip acts differentially, neutrally or integrally, the downward displacement of the head-pin 11 will open the jaws. When the clip acts inverse-differentially, the downward displacement of the head pin will close the jaws. Setting aside from consideration the case of a clip acting inverse-differentially a comparison of the differential, neutral and the integral action of the clip shows that when it acts differentially, the closing and the opening of the jaws take 40 place much more slowly and at a much smaller angular opening than when it acts neutrally or integrally. At the same time the rope-gripping force of the clip is considerably greater when it acts differentially than when it acts neutrally or integrally. Having these features in view, the present invention aims to provide a clip which, instead of being differential, neutral or integral according to its construction, is capable of acting in three different ways so that the jaws will open and close at different speeds at different stages of operation, while the head pin 11 displaces up and down with uniform speed.

60 Figures 6 and 7 show a car for the double rope system provided with my improved clip. In these figures, the annular bracket 20 which is operably mounted on the front sleeve of the suspension bar 14 is held in 65 its place by means of a nut 19 screwed on

the fore end of the main shaft 12. A pair of wheels 22 are rotatably mounted, in the vertical plane passing through the head pin 11, upon the carriage 24 by means of the pivots 23. In the interior of the carriage 24 a sliding box is provided, at each side of which is a lateral slider with a horizontal pin 26 to move vertically. On the pins 26 are operably mounted the pair of hook bars 25, the lower ends of which are operably mounted on the pins 27 provided on the head-pin 11. By this construction, the pair of hook bars forming a parallelogram transmit the reaction of the carrying rope 2 to the head-pin 11. Through the central slider which move up and down in the sliding box in the carriage 24 passes the supporting shaft 29 at both ends of which the side wheels 28 are rotatably mounted. The projections of the supporting shaft 29 and of the annular bracket 20 are pivotally connected by means of a pair of supporting bars 21. In this manner the weight of the receptacle is supported by a pair of side rails 4 through the medium of the side wheels 28.

90 Figures 8 to 10 show a car for the single rope system provided with my improved clip. In this car the bracket 20 which is operably mounted upon the sleeve of the suspension bar 14 is held in its place by the head of the main shaft 12. At each end of the bracket 20 is provided the pin 29 upon which the side wheel 28 is rotatably mounted.

95 The pair of wheels 22 and side wheels 28 are placed on the same side of the head-pin 11, the wheels 22 being wider apart from the head-pin 11 than the side wheels 28 are. The carriage 24 is rigidly connected with the extension of the vertical lever-arm 7 by means of a pair of bars 25.

100 In the single rope system because of the absence of the carrying rope the pair of the side wheels 28 would be subject to random oscillations whenever liberated from the side rail 4, unless some means were specially provided to avoid such oscillations. As such means the working bar 30, the connecting bar 31, the compression bar 32, the guide bar 34 and the compression spring 33 are provided. Such combination will adjust the position of the bracket 20 relative to the intermediary arm 15. This resilient means permits a temporary displacement of the bracket 20 relative to the intermediary arm 15, but the bracket automatically resumes its 110 normal position when the external force ceases to act.

115 Now the action of the above mentioned car for the single rope system may briefly be explained.

120 On arriving at a station, the weight of the receptacle will be supported by the side rail 4 which is laid at a convergent angle to the in-coming hauling rope. Owing to the gradual depression of the head-pin 11 the 130

clip jaws will open, thus releasing the hauling rope 1. An analysis of this action which will not take more than the twinkling of an eye to complete, shows two stages of operation, in the first of which the eye-bars 18 will displace so as to gradually decrease its inclination toward the vertical lever-arm 7, becoming more nearly parallel to the bottom of the trapezoid. The clip at this stage of 5 operation behaves entirely as a differential clip until the neutral line is reached. As soon as the neutral line is passed the second stage of operation commences, the eye-bars 18 gradually displacing from the position parallel to the bottom of the trapezoid to one of downward incline, and the jaws open completely. In this second stage of operation the clip beginning theoretically with a neutral action changes its action into that 10 of an integral clip and, consequently, the jaws open much more rapidly than in the first stage of the operation.

When leaving a station, the car of the above description marching by its own inertia toward the hauling rope which is running forward at a divergent angle to the side rail 4, enters the bent path 2 and brings the pair of wheels 22 into contact with the main rail 3 of the said bent path. 15 In consequence the carriage 24 becomes parallel to the hauling rope 1, and the head-pin 11 being pressed down, the clip jaws 5 and 6 comes into contact with the hauling rope with widely open mouth. When such contact takes place, the hauling rope exerts upward pressure on the jaws, which in cooperation with a part of the downward pressure of the main rail 3 produces a couple that ensures a sure gripping of the 20 clip on the hauling rope. This couple increases gradually in proportion to the increase of the upward pressure of the hauling rope and acts on the suspension bar 14, thereby causing the center of gravity of the 25 receptacle to displace from the vertical plane passing through the side rail 4 to that passing through the hauling rope 1. The upward pressure of the hauling rope causes the clip jaws to shut and prepares the hauling rope to assume the burden of the entire 30 weight of the receptacle. No sooner than the weight of the receptacle is transferred from the side rail 4 to the hauling rope 1 the downward pressure of the jaws 5 and 6 35 causes them to close differentially and grip the hauling rope. The operation of the clip, upon departure of a car from a station, may be analyzed into two successive stages as upon its arrival at a station, though the 40 change from one stage to the other takes place in the reverse order. During the first stage of operation in which the eye-bars 18 gradually displace from a stooped position to a position parallel to the bottom 45 of the trapezoid, the clip acts integrally.

During the second stage of operation in which the eye-bars gradually displace to a position turned upward in regard to the bottom, the clip acts differentially. The amount of the gripping force with which 50 the jaws are able to act on the hauling rope is in inverse proportion to the speed with which the jaws close in the different stages of the operation.

Having thus particularly described and ascertained the nature of my said invention and in what manner the same is to be performed, I declare that what I claim is—

1. A clip comprising a horizontal lever-arm having a jaw, a vertical lever-arm also having a jaw, an arm joining the horizontal lever arm at the end opposite its jaw, and an arm pivotally interconnecting the said arm and the vertical lever arm, so constructed that the head pin which connects the two jaws pivotally, and the tail-pins of the three arms form the vertices of a trapezoid quadrilateral, of which the line connecting the tail-pin of the intermediary arm and the tail-pin of the horizontal lever-arm forms 90 the immovable lateral side while the vertical lever-arm forms the movable lateral side, the said clip operating in such a manner that its jaws will close when the eye-bars forming the upper side of the trapezoid turn upward away from the bottom, and the jaws will open when the said eye-bars turn down toward the said bottom.

2. A clip comprising a horizontal lever arm having a jaw, a vertical lever-arm also having a jaw, an arm joining the horizontal lever arm at the end opposite its jaw, and an arm pivotally interconnecting the said arm and the vertical lever arm, so constructed that the head-pin which connects the two jaws pivotally, and the tail-pins of the three arms form the vertices of a trapezoid quadrilateral of which the line connecting the tail-pin of the intermediary arm and the tail-pin of the horizontal lever-arm forms 100 the immovable lateral side while the vertical lever-arm forms the movable lateral side, the said clip operating differentially, that is to say the two jaws rotating in the same direction to approach each other, when the tail-pin of the vertical lever-arm rises above the straight line passing through the tail-pin of the intermediary arm and running parallel to the bottom of the trapezoid, 110 while the clip will act integrally, that is to say the two jaws will rotate in the opposite directions and recede from each other, when the tail-pin of the vertical lever-arm sinks below the straight line passing through the tail-pin of the intermediary arm and running parallel to the bottom of the trapezoid.

3. In a device of the character described, the combination of a shaft, a bracket pivotally mounted on the shaft and extending upwardly therefrom, a suspension bar pivot-

tally mounted on the shaft and depending therefrom, a horizontal lever arm pivotally mounted at the end of the shaft for movement in a plane through the latter and having a jaw at its free end, a vertical lever arm having a jaw pivotally connected to the said jaw, an arm joining the horizontal lever arm near its pivot and having a fixed angular relation to the shaft, and an arm pivotal-

ly interconnecting the said arm and the vertical lever arm.

4. Arrangement according to claim 3 in which the bracket has a central opening in which the lever system defined is angularly movable.

In testimony whereof, I affix my signature.

YUSUKE TAMAMURA.
